UNITED STATES PATENT OFFICE.

GEORGE F. KRIEGER, OF CHICAGO, ILLINOIS.

DESIGN FOR A CIGAR-LIGHTER.

SPECIFICATION forming part of Design No. 26,219, dated October 27, 1896.

Application filed March 23, 1896. Serial No. 584,556. Term of patent 31 years.

To all whom it may concern:

Be it known that I, GEORGE F. KRIEGER, a citizen of the United States, residing at Chicago, in the county of Cook and State of Illinois, have invented and produced a new and original Design for Cigar-Lighters, of which the following is a specification.

The accompanying drawing is a perspective view from the front of a cigar-lighter, illustrating my design.

The leading feature of my design consists in an ornamental base upon which are placed the figures of a man and of a woman inclined toward each other in the act of lighting a cigar. Certain other features add both to the beauty and usefulness of the design, and consist in a cylindrical box at the middle of the front of the base, held within scrolls of the base and provided with apertures and knives for cutting off the tips of the cigars before they are lighted.

The design further consists in small dishes or shell-shaped receptacles formed upon each end of the base, which serve to extend the base in an ornamental manner at each side of the figures of the man and woman and also serve to receive matches for lighting the gas-jet of the cigar-lighter, which in the illustration is caused to issue from the top of the hat of one of the figures.

The base A comprises a central disk or dome B, encircled with foliage a; two shell-shaped dishes C, placed one at each side of the base; two reversed foliated-scrolls D, extending from the front and middle portion of

the base and surrounding an upwardly-projecting cylindrical box E or case, forming the cigar-tip clipper, the space between the dome A and dishes C, scrolls D, and box E being ornamented by two reversed ribbon-scrolls 40 F, and the back of the base is finished with scrollwork or foliage similar to the ribbon-scrolls at the front. The dishes C are also preferably ornamented at their outer edges with foliage, as shown. Between the end 45 dishes C and the central disk or field B are placed two foliated brackets G, G, one upon each side of the base, secured thereto and supporting, respectively, the figures of a man H and a woman I, bending toward each other 50 and each holding in the mouth a cigar. The arm of the man is extended toward the face of the woman, with the hand supporting the chin, and the arm of the woman is extended with the hand holding the arm of the 55 man. The dress of the figures and the foliage and scroll ornamentation may be varied to suit the fancy without departing from my invention.

What I claim is—

The design for a cigar-lighter herein shown and described.

In testimony that I claim the foregoing as my invention I have signed my name in the presence of two subscribing witnesses.

GEORGE F. KRIEGER.
